US0D1076908S

(12) **United States Design Patent** (10) Patent No.: **US D1,076,908 S**
(45) Date of Patent: ** May 27, 2025

(54) **ALL-IN-ONE COMPUTER**

(71) Applicant: **Lenovo (Beijing) Limited**, Beijing (CN)

(72) Inventor: **Yizhou Ye**, Beijing (CN)

(73) Assignee: **Lenovo (Beijing) Limited**, Beijing (CN)

(**) Term: **15 Years**

(21) Appl. No.: **35/522,042**

(22) Filed: **Jun. 28, 2024**

(80) **Hague Agreement Data**

Int. Filing Date: **Jun. 28, 2024**

Int. Reg. No.: **DM/239238**

Int. Reg. Date: **Jun. 28, 2024**

Int. Reg. Pub. Date: **Aug. 23, 2024**

(30) **Foreign Application Priority Data**

Dec. 29, 2023 (CN) 202330870699.7

(51) **LOC (15) Cl.** **14-02**

(52) **U.S. Cl.**

USPC **D14/336**; D14/371
